UNITED STATES PATENT OFFICE

161,756

ROTARY SPIT

William H. Hunter, Flushing, Mich.

Application March 17, 1950, Serial No. 8,590

Term of patent 14 years

(Cl. D81—10)

To all whom it may concern:

Be it known that I, William H. Hunter, a citizen of the United States of America, residing at Flushing, county of Genesee, State of Michigan, have invented a new, original, and ornamental Design for a Rotary Spit, of which the following is the specification, reference being had to the accompanying drawing, forming a part hereof.

Fig. 1 is a plan view of a rotary spit, showing my new design.

Fig. 2 is a side view as seen in Fig. 1.

Fig. 3 is a front end view, and

Fig. 4 is a rear end view thereof.

I claim:

The ornamental design for a rotary spit, as shown.

WILLIAM H. HUNTER.
